UNITED STATES PATENT OFFICE.

CHARLES E. VAN NORMAN, OF SPRINGFIELD, MASSACHUSETTS.

METAL-WORKING MACHINERY.

938,803.

Specification of Letters Patent.

Patented Nov. 2, 1909.

Application filed March 20, 1909. Serial No. 484,829.

To all whom it may concern:

Be it known that I, CHARLES E. VAN NORMAN, a citizen of the United States of America, and resident of Springfield, in the county 5 of Hampden and State of Massachusetts, have invented certain new and useful Improvements in Metal-Working Machinery, of which the following is a full, clear, and exact description.

10 The present improvements in metal working machinery are especially applicable in machines comprising as a tool or instrument which operates on the work a rotary grinding wheel available for grinding external 15 round surfaces or internal round surfaces; and a machine of the general character to which this invention pertains is one having a suitable supporting frame or base, a bed mounted and having reciprocatory 20 movement longitudinally on the base and having work supporting means, which may be a head stock for a chuck, or a head stock and a tail stock on which the work may be mounted between centers; means for imparting 25 endwise back and forth motions to the bed, and a transversely slideable support on which is mounted a head carrying a spindle for the rotary grinding wheel or other rotary tool and which operates on the work, which 30 spindle has in conjunction therewith means for securing a very rapid rotation thereof.

A leading object of the invention is to provide an improved mechanism for varying, at pleasure, the extents of endwise movement of the bed so that the work mounted thereabove may have comparatively long or short reciprocatory movements in relation to the rotary grinding wheel, or so that, if desired, while the machine is running in its 40 regular way the bed carrying the work will have absolutely no endwise movement, as may be desirable in cases where, for instance, an annular groove is to be ground into a shaft.

45 Another object of the invention is to provide improved means whereby the bed may be temporarily disconnected from the mechanism which imparts the reciprocatory movement thereto, and to provide in conjunction therewith independent means for endwise moving the bed so that the same may be positioned bodily at any desired location within reasonable limits along the 50 length of the supporting frame, whereby on restoring the connection between the bed

and its reciprocating means, the work, or the portion thereof to be operated upon, will be in proper relation therefor to the grinding wheel.

Another object of the invention is to provide in conjunction with the improved mechanism for imparting reciprocatory movements to the work carrying bed, means for varying the speed of operation of such mechanism whereby the passes of the work relatively to the grinding wheel will be comparatively fast or comparatively slow as may be most effective for the desired results.

Other objects of the invention are to the end of rendering the machine entirely practical, comparatively simple and inexpensive of construction, and susceptible of very quick and convenient management.

The invention consists in combinations or arrangements of parts and the constructions of certain of the parts all substantially as hereinafter described in conjunction with the accompanying drawings and set forth in the claims.

In the drawings:—Figure 1 is a front elevation of the machine, the tail stock being understood as removed; and an annular piece to be internally worked upon represented as carried by the head stock. Fig. 2 is a plan view of the machine, the work carrying bed being understood as absent for the purpose of the better disclosing the novel mechanisms,—a portion of the frame at the rear being broken away and represented in section for clearer illustration. Fig. 3 is substantially a vertical longitudinal section of the complete machine as taken on line 3—3, Figs. 2 and 4,—the tail stock being shown as in its place on the bed and a shaft-like piece being mounted between centers to be externally ground. Fig. 4 is a transverse vertical section on line 4—4, Fig. 2; Fig. 5 is a vertical sectional view longitudinally through a rear portion of the machine as taken on line 5—5, Fig. 2, and as seen in the direction indicated by the arrow. Fig. 6 is an end elevation of the machine. Fig. 7 is a perspective view showing the principal portions of the mechanism for reciprocating the work carrying bed in predetermined varying extents. Fig. 8 is a partial longitudinal sectional view with some parts in side elevation, as taken on line 8—8, Fig. 4.

Similar characters of reference indicate corresponding parts in all of the views.

In the drawings,—A represents a supporting frame or base of the machine having on the long horizontal top thereof a slideway a^2 for a longitudinally reciprocating bed B on which the work is mounted and rotated while being operated upon by the grinding wheel or other tool provided in the machine.

The bed B, as indicated in Figs. 3 and 4, 10 comprises a lower table-like section a^2 and a table-like section a^3 superimposed thereon and connected therewith by a swivel stud a^5 so that the upper section of the bed on which the head stock C and the tail stock C² are 15 mounted, may be swung so that the axes of the head stock and tail stock spindles may within suitable limits be more or less oblique to the central longitudinal horizontal line of the machine. This formation of the two- 20 part bed with one section thereof swiveled centrally on the other is somewhat common in the general class of metal working machinery to which the present improvements pertain.

25 The base or frame of the machine is provided with a rearward extension A² on ways of which are mounted a transversely slidable support D for the grinding mechanism,—this support comprising a lower bed-like section D² having a rack bar b engaged with which is a gear wheel b² on a shaft b³ which at its outer end has a worm wheel b⁴ engaged by the worm b⁵ on a horizontal shaft b⁶ horizontally and transversely mounted on 30 the right hand end of the machine and provided with a hand wheel b⁷,—such support furthermore comprising the bed-like section D³ superimposed on the section D² and slidable thereon transversely of the machine,—the section D² being penetrated by 35 the vertical stud c having a head at its lower end engaged in the T-groove e² in the sections D², the upper end of the stud being screw threaded and receiving thereon the lever nut e³, the tightening of which locks the one section D³ on the other one D².

40 A head E in which a spindle E² for the grinding wheel α is mounted for rapid rotation is by its bar-like extension c pivotally 45 mounted at c² on the upper section D³ of the transversely adjustable grinding-mechanism-support.

The part D³ has a bracket arm c⁴ extending under the swinging head, provided with 50 an adjustable stop, constituted by the screw c⁵ for determinatively positioning the head when swung forwardly and downwardly for its working relation to the work to be operated upon.

55 60 The pinch screw or screws c⁶ are operative to bind the grinding wheel spindle carrying head in its properly set position for the working of the machine. The grinding wheel spindle E² has small pulleys E⁴ at its end portions; and to the rear of these

65 pulleys E⁴ are very much larger pulleys E⁵, both mounted on the same shaft E⁶ journaled in bearings of the part D³ and rotated by belt and pulley E⁷, E⁸, shown in Fig. 4. The belts E⁹ running around the large pulleys E⁵, and also around the very much smaller pulleys E⁴ on the spindle E² drive the grinding wheel at great speed.

70 Proceeding to describe the novel mechanism for imparting the reciprocation to the bed longitudinally and with varying lengths of strokes, as predetermined:—F represents a bar longitudinally slidable through guideways f therefor in the machine frame centrally beneath the bed; and this bar is to be 75 considered as an appurtenance of the bed, and as a fixture thereof excepting as to capabilities for its disconnection temporarily from the bed as, and for the purpose, hereinafter explained. As shown, the slidable bar F has the upstanding separated lugs f², f² which have engagement with a depending lug g of a bar G which for the present is to be considered as a part of, and as one with the lower section a² of the bed, 80 all so that endwise movements of any extent imparted to the slidable bar F imparts corresponding movements to the bed as a whole, and to the piece of work mounted thereon.

85 The slide bar F has a transversely extending and depending engagement member h adjacent which is a rotary cam H arranged in a horizontal plane and at the upper end of the vertical shaft H² to which rotation is imparted at any speed determined on by means hereinafter fully described.

90 A lever J is pivoted at i on a fixed support i² therefor, and such lever extends from its pivot horizontally and substantially transversely of the machine over and in proximity to the rotary cam H which is arranged in a horizontal plane and has its cam groove or path j upwardly opening receiving therein the roller stud j² which depends from the extremity of the lever by which it is carried. The lever has a longitudinal integrally formed rib k, preferably of dove-tail shape, on which a block L is engaged and slidably guided for movement lengthwise on the lever and having by its 95 upstanding stud k² an engagement with the aforementioned transversely extended engagement piece h carried by the slide bar F. 100

105 M represents a screw shaft which engages through the said block,—the turning movement of which shaft causes the block L which carries the stud k² to be moved endwise along the length of the lever J to have 110 its position nearer or farther from the pivot i or in some cases, as desired, coincident with the pivot.

115 M² represents a comparatively short horizontally arranged shaft-section, connected 120

by a double universal joint m to the forward end of the screw shaft,—this shaft section M^2 having a comparatively small spur gear m^2 thereon; and it may be moreover said of this shaft section that it is mounted in the journal bore m^3 at the front of the machine frame whereby it may have a slight degree of axial movement which, incidentally, it derives by being universal-joint-connected to the screw shaft which has bodily an oscillation in unison with the cam actuated swinging lever J .

N represents another comparatively short horizontal shaft below the shaft section M^2 , the same having affixed thereon a gear wheel N^2 larger than the one m^2 ; and said shaft N has a hand wheel N^3 at its outer end, at the front of the machine for conveniently turning it. This speed increasing gearing between the hand wheel N^3 and the screw shaft M is for securing a quick adjustment of the block L in its relation to the lever pivot, although, of course, as apparent, the shaft section M^2 might be directly operated for a slower block adjusting operation.

When the block L is positioned comparatively far from the fulcrum point i of the cam-operated lever, the bed, and the work 30 bodily carried thereby (as well as rotated thereon), will have a long pass relatively to the edge of the grinding wheel rotating at a fixed position, while the length of the pass of the work will be lessened proportionately 35 as the location of the block L is nearer the lever fulcrum; and in cases where it is desired to grind a peripheral groove, in a shaft or cylindrical piece, the machine may be run without imparting any endwise movement 40 to the bed and the piece carried thereby, to be worked upon, by establishing the conditions therefor as accomplished by,—through the screw shaft,—securing a position of the block coincident with the axis of 45 the lever pivot i .

While in the description before given but one transverse engagement piece h has been referred to as subject to forcing action by the stud h^2 of the lever carried block L for 50 moving the bed in one direction, only, in order to make the machine adequate and efficient a means manifestly should be included for oppositely endwise moving the bed for the return passes of work relatively 55 to the grinding wheel; and while for the return movement of the bed a spring might be retractively employed I have provided as preferable thereto and as shown in Figs. 2 and 3 a transverse horizontal depending engagement member h' as an equipment of the slide-bar F (and which is a counterpart of the one h which is most clearly shown in Fig. 7,) and which has its location relatively 60 to the one h so close thereto as to constitute 65 with such part h an opposite wall of a trans-

verse channel upwardly into which extends the roller stud of the lever carried block L .

For the purpose of rendering the machine more nearly universally available for grinding cross-sectionally circular pieces of varying lengths and for grinding at any desired place on the length of the piece, provision is made for temporarily disconnecting the bed from the mechanism which imparts the longitudinal reciprocatory movements thereto, so that the bed may be bodily slid as far as appropriate endwise in either direction whereupon after the securing of a proper positioning of the work relatively to the position of the grinding wheel, the bed is again placed in connection with the reciprocating mechanism, which has been fully described, therefor.

The expedient last above referred to will be seen to be carried out by provisions as follows: The bar G hereinbefore once mentioned, is, as a matter of fact, separately formed from the lower section α^2 of the bed and is slidably fitted, in the manner of a gib, in a straight longitudinal way α therefor which has the form of a wide groove or channel in the lower portion of the bed.

P represents a block having, at its vertically widened side, an engagement against the rear side of the bar G ,—the portion of this block extending over and across the top of the bar, and it is engaged by the screw threaded stem or small shaft P^2 , a shoulder at the outer extremity of which engages against the outer face of the machine frame,—said screw threaded stem P^2 having a handle extension P^3 for conveniently turning it.

By the turning in the proper direction of the screw threaded stem, the clamp block P is caused to bind the bar G sidewise against the wall of the way in which it is fitted at its front, so that the bed must partake of any endwise movements which the slideable bar F derives from the operating mechanism therefor.

When the clamp block is loosened so that the carriage is slidably free relatively to the bar G , which always remains in its given location, the carriage may be bodily moved without affecting the mechanism which normally operates it, and without being affected thereby through means of the engagement with the rack bar Q thereon of the pinion Q^2 mounted on a short horizontal shaft Q^3 which has a hand wheel Q^4 at its outer end whereby it may be conveniently manually turned. The small gear wheel or pinion Q^2 and its shaft and hand wheel are free and incidental to the regular operation of the machine have back and forth rotary movements because of the engagement with the rack carried on the underside of the carriage, with the pinion. The vertical shaft H^2 ,—on the upper end of which the cam H 130

is carried by bevel gearing R , R^2 , connected with a rearwardly located horizontal shaft S on the rear end of which is a disk S^2 .

T represents a shaft ranging horizontally 5 and longitudinally at the rear of the machine and driven by belt T^2 and pulley T^3 .

U represents a wheel edgewise frictionally running on the face of the disk, this wheel being spline engaged on the shaft T which 10 is arranged crosswise of and in proximity to the face of the disk, so that while the friction wheel must always rotate as one with the shaft it may be positioned for its peripheral frictional engagement on the face 15 of the disk either near to or comparatively far from the disk axis. The friction wheel is set in its required position relatively to the axis of the disk through means of a yoke U^2 , carried on a bar U^3 which is slidable 20 above and parallel with the shaft T ,—the depending members of the yoke embracing or engaging the friction wheel. The bar U^3 has rack teeth t at its lower edge in mesh with which is a spur gear wheel or pinion u 25 on the horizontal shaft u^2 horizontally and transversely extended to the front of the machine and provided with a hand wheel u^3 .

By turning the hand wheel u^3 in the proper direction, the speed of the cam carrying shaft H^2 may be regulated to result in 30 the reciprocations of the carriage and the work mounted thereon for fast passes or slow passes relatively to the grinding wheel as may be best suited to the desired working 35 results.

Referring to Fig. 3, a long shaft-like piece y is shown as being carried between the head stock and tail stock center, and its movements as carried by the bed are on the line 40 of its axis, but if the piece were to be ground on, or to form, an external tapered shoulder the upper section of the bed would be swung more or less on its swivel stud a^5 so that the line between the head and tail stock would 45 be properly oblique to the longitudinal median line of the machine corresponding to the taper or beveling of the external surface to be ground.

In a case such, for instance, as indicated 50 in Fig. 1, where a hollow cylindrical piece v is to be internally ground, such piece is carried by a chuck with which the head stock is provided, the tail stock is removed by being slid off at the right hand end of the machine and the sliding support D for the grinding mechanism is moved forwardly to bring the grinding wheel to the proper working position.

This machine would be operative and useful in degree if the parallel transverse engagement members h , h^2 were formed as dependent members directly upon the under portion of the bed; but, of course, by the provision as appurtenances of the bed, of 60 the bar G , detachably connected to the bed

and the slide bar F having its engagement with the bar G , the capabilities of the machine are largely augmented.

I claim:

1. In a machine of the character described, 70 a longitudinally slidable member, appurtenant to the movable work supporting bed, provided with a transversely extending engagement piece, a rotary cam, a pivoted lever, engaged by and deriving a swinging movement from, said cam, a block slidably guided for movement lengthwise of the lever and having an engagement with said engagement piece, for endwise moving the longitudinal slidable member, and means for 80 variably positioning said block along the length of the lever.

2. In a machine of the character described, 85 a longitudinally slidable member, appurtenant to the movable work supporting bed, provided with separated parallel transverse engagement pieces, a rotary cam, a pivoted lever, engaged by and deriving a swinging movement from, said cam, a block slidably guided for movement on, and lengthwise of, 90 the lever, and having an engagement between said engagement pieces, and means for variably positioning said block along the length of the lever.

3. In a machine of the character described, 95 a longitudinally slidable member, provided with a transversely extending engagement piece, a rotary cam, a pivoted lever, engaged by and deriving a swinging movement from, said cam, and having a slide rib extending 100 along the length of the lever, a block slidably guided for movement lengthwise along said rib and having a projection in engagement with said engagement piece, and means for variably positioning said block along 105 the length of the lever.

4. In a machine of the character described, 110 a longitudinally slidable member, appurtenant to the movable work supporting bed, provided with a transversely extending engagement piece, a rotary cam, a pivoted lever, engaged by and deriving a swinging movement from, said cam, a block slidably guided for movement lengthwise on the lever and having an engagement with said 115 engagement piece, for endwise moving the longitudinally slidable member, and a screw having an engagement with said block for positioning the latter variably along the 120 length of the lever.

5. In a metal working machine, a bed and 125 a support having longitudinal ways on which said bed is slidably supported, a member and means for detachably connecting it as one to the bed, a bar, slidably supported, and engaging said detachably connected member, adjustable means for imparting endwise movement, in variable predetermined extents to the bar, and independent means by which the bed may be freely end- 130

wise moved on the disconnection from the latter of said detachable member.

6. In a metal working machine, a support having slideways for a bed, and a bed 5 slidable thereon having a longitudinal way and a member fitted to said longitudinal way of the bed, and means for connecting it as one to the bed, a bar, slidably supported beneath the bed, and engaging said detachably 10 connected member, adjustable means for imparting endwise movements, in variable predetermined extents to the bar, and independent means by which the bed may be freely endwise moved on the disconnection from 15 the latter of said detachable member.

7. In a metal working machine, a support having a slideway for a bed and a bed slidable thereon, having a longitudinal way and provided with a rack, a member slidably 20 fitted to the way of said bed and means for detachably connecting it as one to the bed, a bar, slidably supported, beneath, and engaging said detachably connected member, adjustable means for imparting endwise 25 movements, in variable predetermined extents to the bar, a gear wheel in mesh with the rack provided on the bed, and means for rotating said gear wheel.

8. In a metal working machine, a support 30 having a slideway for a movable bed and a bed slidable thereon provided with a rack, and having a longitudinal way a member fitted to said way, a block sidewise engaging said member for a clamping bind thereof by 35 its side against a side of the way in which such member is fitted, a shaft rotatably mounted in the bed, having a screw engagement with said block to operate it for its clamping and unclamping action, a bar, slidably supported, and engaging said clamped 40 member, adjustable means for imparting endwise movements, in variable predetermined extents to the bar, a gear wheel in mesh with said rack and means for rotating 45 the gear wheel.

9. In a machine of the character described, a longitudinally slidable member, appurtenant to the movable work supporting bed, provided with a transversely extending 50 engagement piece, a rotary cam, a pivoted lever, engaged by and deriving a swinging movement from, said cam, a block slidably guided for movement lengthwise on the lever and having an engagement with said engagement 55 piece, for endwise moving the longitudinally slidable member, a screw-shaft having an engagement with said block for positioning the latter variably along the length of the lever, another shaft endwise related 60 and universal-joint-connected to said screw shaft, and means for rotating the latter shaft.

10. In a machine of the character described, a longitudinally slidable member, 65 provided with separated parallel transverse

engagement pieces, a rotary cam, a pivoted lever, engaged by and deriving a swinging movement from, said cam, a block slidably guided for movement on, and lengthwise of, the lever, and having an engagement between 70 said engagement pieces, a screw shaft engaging said block, a shaft section endwise related, and universal-joint-connected to, the screw shaft, provided with a small gear wheel, another shaft parallel with said shaft 75 section having a larger gear wheel thereon, and means for rotating the latter shaft.

11. In a machine of the character described, a longitudinally slidable member, provided with separated parallel transverse 80 engagement pieces, a rotary cam, a pivoted lever, engaged by and deriving a swinging movement from, said cam, a block slidably guided for movement on, and lengthwise of, the lever, and having an engagement between 85 said engagement pieces, a screw shaft engaging said block, a shaft section endwise related, and universal-joint-connected to, the screw shaft, provided with a small gear wheel, a supporting bearing for said shaft 90 section in which the latter is axially movable, another shaft parallel with said shaft-section having a larger gear wheel thereon, and means for rotating the latter shaft.

12. In a machine of the character described, a longitudinally slidable member, appurtenant to the movable work supporting bed, a rotary cam, a pivoted lever, engaged by and deriving a swinging movement from, 95 said cam, a block slidably guided for movement on the lever, for varying its distance from the lever fulcrum and coacting with said slidable member for longitudinally moving the latter, and means for variably positioning said block along the length of the 100 lever.

13. In a metal working machine, a bed having a depending lug and a supporting frame having longitudinal slideways for the bed, a bar longitudinally ranged, and slidably supported, beneath the bed having an upstanding member engaging said depending lug and having a pair of transverse parallel depending members, a pivoted lever, a rotative cam coacting with said lever for imparting swinging movements thereto, a block supported by, and slidable along the length of, the lever, having an upstanding roller stud engaging between said parallel depending members, a screw shaft engaging through 115 said block, and means for turning said shaft for positioning said block variably along the length of the lever.

14. In a metal working machine, a supporting frame having longitudinal slide- 120 ways for a bed, and a bed comprising a lower horizontal section having a depending lug, and a superimposed section centrally pivoted engaged on the lower bed section and having work carrying means mounted 125 130

- thereon, a bar ranged longitudinally, and slidably supported beneath the bed having an upstanding member engaging said depending lug and having a pair of transverse parallel depending members, a pivoted lever, a rotative cam coacting with said lever for imparting swinging movements thereto, a block supported by and slidable along the length of the lever having an upstanding roller stud engaging between said parallel depending members, a screw shaft engaging through said block, and means for turning said screw shaft.
15. In a metal working machine, a supporting frame or base having a bed longitudinally movable thereon and a work carrying support mounted on the bed, means for moving the bed longitudinally on the frame, a support slidably movable transversely on the frame, having a head for a tool carrying spindle pivotally mounted on said support whereby said head may be swung toward and away from the location of the work, said support having a stop for determinatively positioning such swinging head in its relation to the work and means for transversely moving said support.
16. In a machine of the character described, a longitudinally slidable member, a rotary cam, a lever engaged by, and deriving a swinging movement from, said cam, a block slidably guided for movement on the lever for varying its distance from the lever fulcrum, and coacting with said slidable member for longitudinally moving the latter, means for variably positioning said block along the length of the lever, and mechanism for rotatably driving said cam, which comprises adjustable speed varying means.
17. In a machine of the character described, a longitudinally slidable member, a cam, a lever engaged by, and deriving a swinging movement from, said cam, a block slidably guided for movement on the lever for varying its distance from the lever fulcrum, and coacting with said slidable member for longitudinally moving the latter, means for variably positioning said block along the length of the lever, a rotative shaft on which said cam is mounted, a shaft gear connected to the cam shaft having a disk thereon, a wheel edgewise frictionally running on the face of the disk, adjustably mounted to be positioned variably relatively to the disk center, and means for rotating said wheel.
18. In a machine of the character de-

scribed, a slidable member appurtenant to the work carrying part of the machine, a cam, adjustable devices between the cam and said member for imparting variable extents of movement to said member, a disk having a driving connection with said cam, a wheel edgewise frictionally running on the face of the disk, a shaft on which said wheel is axially adjustably movable but relatively to which the wheel is non-rotatably engaged, means for rotating said shaft, and means for adjusting the friction wheel, along the length of its shaft, toward and away from the center of said disk.

19. In a machine of the character described, a longitudinally slidable member, a cam, a lever engaged by, and deriving a swinging movement from, said cam, a block slidably guided for movement on the lever for varying its distance from the lever fulcrum, and coacting with said slidable member for longitudinally moving the latter, means for variably positioning said block along the length of the lever, a rotative shaft on which said cam is mounted, a shaft, gear-connected to the cam shaft having a disk thereon, a wheel edge-wise frictionally running on the face of the disk, a shaft, on which said wheel is spline engaged, and means for rotating such shaft, a slidable bar carrying a yoke which embraces the wheel, and means for manually sliding said bar.

20. In a machine of the character described, a longitudinally slidable member, a cam, a lever engaged by, and deriving a swinging movement from, said cam, a block slidably guided for movement on the lever for varying its distance from the lever fulcrum, and coacting with said slidable member for longitudinally moving the latter, means for variably positioning said block along the length of the lever, a rotative shaft on which said cam is mounted, a shaft gear connected to the cam shaft having a disk thereon, a wheel edgewise frictionally running on the face of the disk, a shaft, on which said wheel is spline engaged, and means for rotating such shaft, a slidably mounted rack bar carrying a yoke which embraces said wheel and a shaft having a hand wheel and a gear wheel in mesh with the teeth of said rack bar.

Signed by me at Springfield, Mass., in presence of two subscribing witnesses.

CHARLES E. VAN NORMAN.
